ROLLER SKATE WHEEL

Carroll M. Bierman, Franklin Square, N. Y.

Application August 24, 1944, Serial No. 551,030

8 Claims. (Cl. 301—5.7)

This invention relates to roller skate wheels in general.

Among the objects of the present invention, it is aimed to provide an improved roller skate wheel which can be readily adjusted for wear from time to time.

It is still another object of the present invention to provide an improved roller skate wheel associated with a light reflecting disk which will, during use, produce an ornamental lighting effect.

It is still another object of the present invention to provide an improved bearing for a roller skate wheel which can be readily assembled by the average unskilled mechanic, produced at comparatively low cost, and be readily adjusted for wear from time to time by the user.

These and other features, capabilities and advantages of the invention will appear from the subjoined detail description of one specific embodiment thereof illustrated in the accompanying drawing in which

Figure 1 is an enlarged side elevation of a wheel made according to the present invention with a part thereof broken away.

Fig. 2 is an enlarged section on the line 2—2 of Figure 1.

Fig. 3 is an enlarged exploded view of the bearing parts in perspective.

Fig. 4 is an enlarged side elevation of one of the bearing parts.

In the embodiment shown, there is illustrated the wheel proper 1 suitable for use in indoor rinks and the like, preferably composed of a fiber substance such as wood. This wheel element preferably is chambered with an annular wall or collar 2 extending from the intermediate enlargement 3, which in turn extends from the outer enlargement 4, the annular recesses 5 and 6 defining the intermediate enlargement 3 from the outer enlargement 4, and the cylindrical chambers 7 and 8 defining the inner wall 2 from the intermediate enlargement 3.

When the wheel member 1 is composed of wood or the like fibrous material, its outer contour and recesses 5, 6, chambers 7 and 8, and central opening in the dependent wall 2 may with facility be turned on the average wood lathe. If the main wheel 1 were composed of a plastic, its outer contour as well as its chambers could be produced by molding, and in turn if the wheel 1 were composed of metal, it might even be drawn.

It is, of course, understood that while it may be preferable to have the wheel member 1 composed of wood or the like fibrous material, this wheel 1 could be composed of other material without de-

parting from the general spirit of the invention, in which case the outer contour as well as chambers would be produced according to the preferred practice determined by the material or composition of the wheel member 1.

The axle 9 of the truck of a roller skate, provided with a diminishing portion 10 having a thread 11 at its end, is operatively connected to the wheel member 1 by the bearing elements now 10 to be described.

In the first place two metal cups are provided, to wit, the cup 12 and the cup 13, which are similar in construction except that the annular flange 14 of the cup 12 has an inner diameter that corresponds to the outer diameter of the flange 15. In fact, the inner periphery of the flange 14 and the outer periphery of the flange 15 are machined so that they will have a machine fit with one another as shown in Fig. 2. Furthermore, as shown in Fig. 2, the outer periphery of the flange 14 corresponds to the inner periphery of the wall 2 and the width of the outer periphery of the flange 14 corresponds to the width of the wall 2, so that when the cups 12 and 13 are nested into one another on opposite sides of the wall 2, they will assume the position and relation shown in Fig. 2. The annular walls 16 and 17 of the cups 12 and 13, respectively, as particularly shown in Fig. 2, preferably are formed to flare outwardly so that the inner annular faces 18 and 19 of the annular walls 16 and 17 are inclined or cone shaped for the purpose hereinafter to be described.

On the diminished portion 10 of the axle 9 of the roller skate truck, there is mounted the thimble 20 which has a socket receiving projection 21 at one end, an annular ball bearing guide way 22, and an extended cylindrical portion 23 provided with external screw threads. The guide way 22 is adapted to receive the collar 24 provided in the present instance with three recesses 25 to receive the ball bearings 26. The thimble 20 in turn has screw threaded mounted thereon the annular roller bearing guide 27 which in turn has mounted thereon the collar 28 similar to the collar 24, also provided with three recesses 29, in the present instance, to receive ball bearings such as the ball bearings 26. The cups 12, 13, the thimble 20 and ball bearing elements 24 and 28 may all be initially assembled on the wheel 1 by merely tightening the guide 27 on the cylindrical portion 23. To manipulate the same, it is only necessary for the attendant to grasp the projection 21 with a wrench or the like and insert a screw driver or spanner wrench into the notches 30 in the face of the guide 27, see Fig. 4. Preferably the collars

24, 28, and walls 18 and 19 are so initially prepared that a suitable working relation will be established when the collars 24 and 28 are spaced from the webs 31 and 32 of the cups 12 and 13, respectively.

In the use of these wheels, in order to take up for wear, it would only be necessary from time to time for the attendant or user of the skate to tighten up the collar 27 on the threaded element 23 in order to take up any unnecessary play and merely re-establish the proper rotative relationship between the ball bearings 26 and the cone shaped faces 18 and 19 of the cups 12 and 13, respectively.

After the bearing elements have so been assembled, the diminished portion 10 of the axle 9 may be positioned in the thimble 20 and the nut 33 turned on the threads 11 to anchor the diminished portion 10 in place in the thimble 20.

The wheel member 1 can be made reversible by locating the wall 2 directly in the middle axially, without departing from the general spirit of the invention. In such case, if due to wear one edge of the wheel 1 became more worn than the other, it would only be necessary to remove the bearing elements 20, 24, 27 and 28, and reverse them so that what formerly was the inside of the wheel in an axial direction would now be the outside of the wheel in an axial direction.

The recesses 5 and 6 also contribute to this reversibility of the wheel member 1. When the bearing elements are assembled as shown in Fig. 2, then the metal collar or frame 34 is secured into the recess 6 and the disk 35, which may be composed of some transparent or translucent material, is pressed into locking engagement in the recess 36 of the metal frame 34. This disk 35, whether opaque or translucent, is preferably provided with a plurality of pockets or recesses to receive decorative elements, such as the light reflecting stones 37. These stones 37, in order to produce a light reflecting effect, may be composed of cut pieces of glass with a mirror backing, or composed of quartz or any other suitable light reflecting substance without departing from the general spirit of the invention. When these light reflecting elements 37 are so positioned in the disk 35, during use, when a beam of light is directed on the same, a very attractive light reflecting effect will be produced. When wheels equipped with these light reflecting stones are used by skaters, not only the movement of the feet of the performers may be more easily followed, but a very attractive light action will be produced to enhance the value of the performance.

As aforesaid, when the wheel element 1 is reversed, it is only necessary to remove the frame 34 and disk 35 and position it as an instance in the recess 5, see Fig. 2. In order to facilitate removing the frame 34 from the wheel member 1 and yet not interfere with the protection afforded by the disk and frame against dust, the frame 34 may be provided with notches 38, see Figure 1, to receive a spanner wrench, in order to turn the frame 34 out of threaded relation with its recess 5 or 6 in the wheel member 1.

The frame 34 and disk 35, of course, serve not only to produce a decorative effect, but also as a dust proof cover, the fit between the frame 34 and the recess 5, 6 when not threaded being a friction or machine fit and similarly the fit between the disk 35 and the recess 36 in the frame 34 being a friction or machine fit. In order to

protect the bearing portion adjacent the axle 9 from dust, any suitable annular member may be secured in the recess 5 if desired, such as the annular disk 38.

In order to anchor the guide 27 against accidental removal, any suitable means such as the lock nut 27' may be provided.

It is obvious that various changes and modifications may be made to the details of construction without departing from the general spirit of the invention as set forth in the appended claims.

I claim:

1. In a roller skate, the combination of a tread forming member composed of wood or the like having an axial chamber, an annular wall dividing said chamber into two compartments, a pair of bearing cups, one for each compartment having outwardly flaring bearing surfaces, a thimble having a ball bearing guide and shank, a ball bearing ring having spaced ball bearing pockets and ball bearings mounted in said pockets between said guide the flaring wall of one of said cups with the shank extending through the opening of the annular wall into the other cup, a guide screw threadedly connected on the end of said shank, and a ball bearing ring having spaced ball bearing pockets and ball bearings mounted in said latter pockets between said latter guide and the flaring walls of the second cup, the proper bearing on the flaring walls being established by the position of the second guide on the shank of the thimble, the thimble having a central opening to receive the axle of a skate truck and be anchored therein.

2. In a roller skate, the combination of a tread forming member composed of wood or the like having an axial chamber, an annular wall dividing said chamber into two compartments, there being an annular recess at the outer edge of each compartment, a pair of bearing cups, one for each compartment having outwardly flaring bearing surfaces, a thimble having a ball bearing guide and shank, a ball bearing ring having spaced ball bearing pockets and ball bearings mounted in said pockets between said guide and the flaring wall of one of said cups with the shank extending through the opening of the annular wall into the other cup, a guide screw threadedly connected on the end of said shank, a ball bearing ring having spaced ball bearing pockets and ball bearings mounted in said latter pockets between said latter guide and the flaring walls of the second cup, the proper bearing on the flaring walls being established by the position of the second guide on the shank of the thimble, the thimble having a central opening to receive the axle of a skate truck and be anchored therein, and disks operatively positioned in the annular recesses to form dust protecting covers for the bearing in the chamber.

3. In a roller skate, the combination of a tread forming member having an axial chamber, an annular wall dividing said chamber into two compartments, there being an annular recess at the outer edge of each compartment, a pair of bearing cups, one for each compartment having outwardly flaring bearing surfaces, a thimble having a ball bearing guide and shank, a ball bearing ring having spaced ball bearing pockets and ball bearings mounted in said pockets between said guide and the flaring wall of one of said cups with the shank extending through the opening of the annular wall into the other cup, a guide screw

threadedly connected on the end of said shank, a ball bearing ring having spaced ball bearing pockets and ball bearings mounted in said pockets between said latter guide and the flaring walls of the second cup, the proper bearing on the flaring walls being established by the position of the second guide on the shank of the thimble, the thimble having a central opening to receive the axle of a skate truck and be anchored therein, a metal frame secured in the annular recess of the outer compartment, and a decorative disk secured in said metal frame, and serving as a cover to protect one side of the bearing from dust.

4. In a roller skate, the combination of a tread forming member having an axial chamber, an annular wall dividing said chamber into two compartments, there being an annular recess at the outer edge of each compartment, a pair of bearing cups, one for each compartment having outwardly flaring bearing surfaces, a thimble having a ball bearing guide and shank, a ball bearing ring having spaced ball bearing pockets and ball bearings mounted in said pockets between said guide and the flaring wall of one of said cups with the shank extending through the opening of the annular wall into the other cup, a guide screw threadedly connected on the end of said shank, a ball bearing ring having spaced ball bearing pockets and ball bearings mounted in said latter pockets between said latter guide and the flaring walls of the second cup, the proper bearing on the flaring walls being established by the position of the second guide on the shank of the thimble, the thimble having a central opening to receive the axle of a skate truck and be anchored therein, a metal frame in the annular recess of the outer compartment, a light transmitting disk mounted in said metal frame, and light reflecting stones mounted in said disk.

5. In a roller skate wheel, the combination of a tread forming member having an axial chamber, an annular wall dividing said chamber into two compartments, a metal cup in each compartment having a flaring bearing wall, a thimble having a guide and having a shank extending through the opening in said annular wall into said other compartment, a guide screw threadedly mounted on the end of said shank, and rings having spaced ball bearing pockets and ball bearings mounted in said pockets between said guides and flaring bearing walls, the thimble having a central opening to receive the axle of a skate.

6. In a roller skate wheel, the combination of a tread forming member having an axial chamber, an annular wall dividing said chamber into two compartments, a metal cup in each compartment having a flaring bearing wall, a thimble

having a guide and having a shank extending through the opening in said annular wall into said other compartment, a guide screw threadedly mounted on the end of said shank, rings having spaced ball bearing pockets and ball bearings mounted in said pockets between said guides and flaring bearing walls, the thimble having a central opening to receive the axle of a skate, there being an annular recess at the outer edge of one of said compartments, and a disk mounted in said recess to cover the bearing portion in one compartment and protect it from dust and the like.

7. In a roller skate wheel, the combination of a tread forming member having an axial chamber, an annular wall dividing said chamber into two compartments, said annular wall having a central opening to receive the axle of a skate truck, two metal cups having telescoping flanges, one cup fitting into each compartment and the telescoping flanges disposed adjacent the inner periphery of said annular wall, the flanges forming bearings for one another and one flange forming a spacing stop between the two cups, said cups having bearing walls flaring outwardly and bearings mounted in said compartments for the axle of the skate truck, said bearings including guides with annular recesses mounted on the axle, annular rings with spaced ball bearing pockets, and ball bearings mounted in said pockets between said guides and flaring bearing walls being adjustable in said compartments to take up for wear and the like.

8. In a roller skate wheel, the combination of a tread forming member having an axial chamber, an annular wall dividing said chamber into two compartments, said annular wall having a central opening to receive the axle of a skate truck, two metal cups having telescoping flanges, one cup fitting into each compartment and the telescoping flanges disposed adjacent the inner periphery of said annular wall, the flanges forming bearings for one another and one flange forming a spacing stop between the two cups, said cups having bearing walls flaring outwardly and bearings mounted in said compartments for the axle of the skate truck, said bearings including guides with annular recesses mounted on the axle, annular rings with spaced ball bearing pockets, and ball bearings mounted in said pockets between said guides and flaring bearing walls being adjustable in said compartments to take up for wear and the like, there being an annular recess at the outer edge of the outer compartment, and a disk operatively mounted in said recess to cover one side of the chamber.

CARROLL M. BIERMAN.
